VALVE CONTROL SYSTEM

Hubert Korndörfer, Berlin, Germany, assignor to
General Electric Company, a corporation of
New York

Application February 24, 1939, Serial No. 258,198
In Germany April 2, 1938

8 Claims. (Cl. 137—139)

My invention relates to valve control systems, more particularly to a control system for regulating the opening and closing of a valve for directing through a brief period of time a jet or blast of fluid under pressure to a circuit breaker or the like, and has for its principal object the provision of a valve control system of the aforesaid character having improved time delay means for effecting definite reclosure of the valve after predetermined operation thereof.

In the operation of high voltage gas blast circuit breakers, for example, wherein the interrupting contacts are separated and subjected to a gas blast by fluid under pressure, such as compressed air, the supply of the compressed air to the breaker is controlled by a valve which can be opened either manually or by remote electric control. In the case of temporary short circuits and excess currents, the switching operations may follow each other very quickly within fractions of seconds. In such operation it is disadvantageous to separate the switch contacts through the full normal opening stroke, since the actuating means of the breaker is subjected to high stresses due to the great acceleration of the moving switch parts and also since there is large consumption of compressed gas due to a number of rapid complete switching operations.

Therefore, in order to conserve the supply of compressed gas and to eliminate excess wear of the circuit breaker, the interrupting contacts are for such temporary circuit faults separated but a fraction of the full opening stroke. That is, the contacts are separated but a sufficient distance to permit the gas blast effectively to interrupt arcing as compared with the usual isolating distance for voltage protection. Since the arc is generally interrupted by a gas blast of very brief duration, the breaker is in readiness for immediate reclosing.

In accordance with my invention the blast control valve, which can be opened by conventional means, is reclosed after a predetermined time by energy storing means that is charged in accordance with the valve opening operation. The energy storing means coacts with a mass having a definite inertia to cause reclosure of the valve after predetermined operation thereof. The operation of the system is independent of varying factors, such as temperature and humidity fluctuations, since the time of reclosure can be definitely and precisely determined by adjusting the acceleration of the mass and the distance through which it moves.

My invention will be more fully set forth in

the following description referring to the accompanying drawing and the features of novelty which characterize my invention will be pointed out with particularity in the claims annexed to and forming a part of this specification.

Referring to the drawing the single figure thereof is an elevational view, partly in section and partly diagrammatic in character illustrating a valve control system embodying the present invention.

In the circuit breaker system illustrated by way of example, a source of fluid pressure, such as a pressure tank, is indicated at 1 for operating a gas blast circuit breaker 2. The circuit breaker per se forms no part of the present invention and can comprise a pair of separable contacts 3 and 4, between which the arc is formed upon opening of the circuit. The fixed contact 3 is of nozzle shape and is insulated at 5 from the cylindrical switch chamber 6. The movable contact 4 is carried by the operating rod 7 to which is also secured a piston 8. The breaker is opened by fluid pressure acting on the piston 8 and is closed through the rod 7 by suitable means. The contacts are connected to the terminals of the exterior circuit as diagrammatically indicated at 9 and 10. Accordingly it will be understood that when gas under pressure is admitted to the cylinder 6, the piston 8 will be depressed to separate the contacts and a gas blast will be directed through the nozzle contact 3 to extinguish the arc thereat. For the purpose of supplying a gas blast impulse of the desired character to the switch chamber 6, a valve 11 is arranged to control the fluid passage 12 leading from the source 1 to the switch chamber. The valve, as shown, is closed and is opened by depressing the valve stem 11' to cause actuation of the breaker in the manner above described.

The opening means for the valve 11 comprises an actuating solenoid 13 and a bell crank 14 pivotally mounted at 15 so as to coact with the upper end of the valve stem 11' at 16. The solenoid 13 is normally biased by a spring 13' to the upper reset position shown and is actuated in response to an overload or fault by means of a current transformer or the like indicated at 17. It will be apparent, of course, that a relay of the conventional type may be used to actuate the solenoid in response to a fault in the main power circuit. Accordingly when the solenoid 13 is actuated in response to a fault, the plunger is depressed against the bias of spring 13' to engage the lower arm of the bell crank 14 and open the valve 11.

During the valve opening operation, an energy storing device or accumulator, generally indicated at 18, is charged so as to be in readiness to initiate the reclosing of the valve at the desired time. The energy storing device 18 comprises a mass-loaded spring 19 that is seated between a flange 20 carried by a reciprocably guided rod 21 and a movable guided casing 22 that likewise encloses the spring. The rod 21 is slidably mounted with respect to the casing 22 and also with respect to a mass 23 of cylindrical form that is seated on the casing 22. The lower end of the rod 21 is connected through a lever 24 to the valve stem 11' at 25 and at 26 through a pin and slot connection to the lever 24.

The lever 24, which is pivoted at 24', therefore causes upward movement of the accumulator rod 21 when the valve is opened to compress the mass-loaded spring 19 by reason of the latched condition of the spring casing 22. The latch for this purpose can comprise simply a pivoted link 27 resiliently biased at 28 toward latched position with respect to a lug 29 secured to the spring casing. The link 27 can be freely suspended at 27' and is provided with a suitable latching portion 29'. Accordingly when the valve 11 reaches the open position, the spring 19 is under compression and charged.

The valve reclosing operation is effected through a linkage including a bell crank 30 pivoted at 30' and a link 31 connected to the crank at 32 and to the valve stem 11' at 33. In the closed position of the valve illustrated, the linkage assumes a position similar to an underset toggle. A tension spring 34 tends to bias the toggle toward the stretched or straightened position indicated by dotted lines, which the linkage assumes when the valve is open. In this position the arm 30'' of the crank 30, which is in the path of the mass 23 is in the dotted line position shown so that it is spaced by distance a from the mass.

The valve reclosing operation is initiated by means of a link 35 having a lost motion connection at 36 with the link 27 so as to cause release of the latch after a predetermined opening of the valve. Upon release of the latch, the spring 19 acts to accelerate the mass 23 and to move the mass through the distance a to engage the crank 30. This movement of the mass through distance a takes place within a definite and predetermined time interval. As the crank 30 is rotated clockwise under impact of the mass, the toggle linkage causes closing of the valve 35 to the position shown. During the valve closing operation the spring 19 is reset by reason of the lever 24 and the spring casing 22 is relatched as it drops again to the initial position shown.

It will be apparent that the reclosing time 30 can be suitably adjusted by adjusting the spring tension, such as by longitudinal adjustment of the flange 20 and by variation of the mass and the distance a through which the mass is accelerated before engaging the crank 30.

It should be understood that my invention is not limited to specific details of construction and arrangement thereof herein illustrated, and that changes and modifications may occur to one skilled in the art without departing from the 35 spirit of my invention.

What I claim as new and desire to secure by Letters Patent of the United States is:

1. In a fluid control system including a valve for admitting fluid under pressure to a fluid passage, means for actuating said valve comprising

an actuating device for moving said valve in one direction, an energy storing device coacting with said actuating means for moving said valve in the opposite direction after a predetermined time including a spring, a mass arranged to be accelerated by said spring, and means for releasing said spring in accordance with predetermined operation of said valve.

2. In a fluid control system including a valve for admitting fluid under pressure to a fluid passage, means for opening and reclosing said valve comprising actuating means for opening said valve, a spring arranged to be stressed during said opening operation, a member having appreciable mass arranged to be accelerated by said spring for causing reclosure of said valve after a predetermined time of operation thereof, and means for releasing said spring in accordance with predetermined operation of said valve.

3. In a fluid control system including a valve for admitting fluid under pressure to a fluid passage, means for opening said valve, a spring arranged to be stressed in accordance with said valve opening operation, means for latching said spring while it is being charged during said valve opening operation, a mass arranged to be accelerated by said spring upon release thereof and means arranged to be actuated by said mass after it has moved a predetermined distance for reclosing said valve.

4. A valve control system for effecting immediate opening and delayed closing of a valve comprising actuating means for opening said valve, a spring arranged to be charged in accordance with the valve opening operation, a mass for loading said spring, and means for releasing said mass loaded spring after predetermined operation of said valve for causing reclosing of said valve.

5. In a fluid blast circuit breaker system, a valve control system for effecting immediate opening and delayed closing of a valve for admitting an arc-interrupting blast to said breaker comprising actuating means for opening said valve, a spring operatively connected to said valve so as to be charged in accordance with the valve opening operation, a mass for loading said spring, means for releasing said mass loaded spring in accordance with predetermined opening of said valve, and means arranged to be actuated after predetermined movement of said mass loaded spring for causing reclosure of said valve.

6. A valve control system for effecting opening and delayed closing of a valve comprising actuating means for opening said valve, a spring arranged to be charged in accordance with the valve opening operation, said spring being mechanically connected to said valve, latching means for holding fixed one end of said spring during the spring charging operation, a mass for loading said spring at said end, means operatively related to said actuating means for releasing said latch in accordance with predetermined opening of said valve and a linkage connected to said valve and adapted to be actuated by said mass loaded spring after determined movement thereof in response to the unlatching operation.

7. A valve control system for effecting opening and delayed closing of a valve comprising actuating means for opening said valve, an energy accumulator including a loading mass operatively connected to said actuating means so as to be charged during the valve opening operation, means for latching said accumulator during said charging operation, means including a lost motion connection between said actuating means

and latching means for releasing said accumulator after predetermined operation of said valve, and means arranged to be actuated after predetermined movement of said loading mass for causing reclosing of said valve.

5. In a valve control system including a valve for admitting an arc-interrupting gas blast to a circuit breaker, means for opening said valve, and mechanical time delay means for reclosing

said valve comprising a mass-loaded spring and means for adjusting the acceleration thereof, means for charging said spring in accordance with the valve opening operation, and means for releasing said spring to initiate movement of said mass after predetermined operation of said valve, said mass after predetermined movement thereof causing closure of said valve.
